The ornamental design for an optical image bar for an electrophotographic printer, as shown and described.

DESCRIPTION

FIG. 1 is an enlarged partial perspective view of an optical image bar for an electrophotographic printer shown in FIG. 2;

FIG. 2 is a top plan view of an optical image bar for an electrophotographic printer showing my new design;

FIG. 3 is a front elevational view thereof;

FIG. 4 is a side elevational view thereof, the opposite side being a mirror image of the side shown;

FIG. 5 is a rear elevational view thereof; and,

FIG. 6 is a bottom plan view thereof.

FIGS. 2, 3, 5 and 6 are broken away to show indeterminate length.

FIG. 1

FIG. 4

FIG. 2

FIG. 5

FIG. 3

FIG. 6
